CLAIM

The ornamental design for a shoe dryer, as shown and described.

DESCRIPTION

FIG. 1 is a front elevation view of the shoe dryer showing the new design;

FIG. 2 is a right side elevation view thereof;

FIG. 3 is a left side elevation view thereof;

FIG. 4 is a rear elevation view thereof;

FIG. 5 is a bottom plan view thereof;

FIG. 6 is a top plan view thereof; and,

FIG. 7 is a front, bottom, and left side perspective view thereof.

The portions of the design shown in broken lines show unclaimed subject matter.
